UNITED STATES PATENT OFFICE.

EDWIN JAMES HULBERT, OF PORTLAND, CONNECTICUT, AND N. AUBIN, OF MONTREAL, CANADA.

IMPROVEMENT IN ADJUSTABLE DIALS FOR TRAVELERS' WATCHES.

Specification forming part of Letters Patent No. 99,902, dated February 15, 1870.

To all whom it may concern:

Be it known that we, EDWIN JAMES HULBERT, of Portland, in the county of Middlesex, State of Connecticut, and AIME NICHOLAS NAPOLEON AUBIN, of Albany, State of New York, temporarily residing at Montreal, Dominion of Canada, have invented an Improved Watch, which we call "Traveler's Chronometer," of which the following is a specification.

The nature and object of our invention consist in so constructing the dial of a watch that the hour of the place of residence of the owner, and that of each of the principal places through which he may travel in an eastern or a western direction, are very simply and plainly indicated without disturbing the hands of said watch, nor making any mental calculation to ascertain the relative time at the different localities.

We obtain the above result by inscribing upon the surface of a segment of a flat ring, attached to the part of the watch bearing the wheel-work and hands, the names of the principal cities on a particular line of travel, and in such positions corresponding with their respective longitude, combined with a dial, on which are inscribed the hours and minutes, and provided with a slit or hole, through which such name alone can be read, while the home-time can be read, as usual, upon the ordinary dial.

Several modifications can be devised in the relative arrangement of the essential parts; but we will indicate the construction which seems to us the most advantageous, as it does not interfere with the wheel-work as usually manufactured, and preserves the position of the figures with the pendant of the watch, thus facilitating the prompt reading of the way-time.

In the accompanying drawings the figures are on an enlarged scale for greater clearness. Figure 1 is a plan of the watch-dial when at place of residence, supposed to be New York. Fig. 2 is a plan of the same when at Chicago. Fig. 3 is a plan of the traveling time-dial. Fig. 4 is a plan of the plate bearing the names of cities. Fig. 5 is a section of the same plate. Fig. 6 is a perpendicular section through the center and pendant of the watch, showing the relative position of the above parts. In the last figure the shaded lines indicate a section

of the case and of the parts fixed to it. The lines not shaded indicate the movable parts.

A is the watch-case. B is the pendant. C is the milled head of a pin bearing a geared pinion, to rotate the plate bearing the wheel-work, the hands, the home-dial, and names of places; D, hour-hand; E, minute-hand; F, way-time dial; f, oblong hole cut into the way-time dial at the twelve-o'clock mark, through which can be read the name of any place inscribed on the longitude-segment, when such name is brought in a line with the said hole; G, home-time dial, concentric with the way-time dial, and attached to the upper plate of the wheel-work by means of the set-screw g. g' is a semicircular or longer slit to admit the set-screw g and allow the adjustment of the twelve-o'clock mark of the home-dial opposite any city in which the owner of the watch may reside; H, way-ring; h h h, independent segment of a ring, on which can be inscribed any number of cities situated upon a certain line of travel, and at such distances from each other as their relative longitude.

Railroad and navigation companies, army or navy officers, or ordinary travelers can insert them or exchange them for such as they may find convenient for a particular voyage. Thus segments adapted for each line of railroad, for the Middle or Southern States, the British Provinces, or principal cities of Europe, or other points of the globe, can be attached in the simplest manner to our watch by any person. It is held in place by a pin, h', and spring h'', or in any other method.

On the edge or under surface, h'', of the way-plate we cut teeth to gear with the pinion c, inserted in the pendant-stem or in any other part of the watch-case. This allows the traveler, by merely turning the milled head C, to bring the names of cities through which he proceeds, either east or west of his home, successively under the hole f, and thus to ascertain the local time without opening the watch or disturbing the hands, which continue to indicate the home-time on the smaller dial. When he returns home, the two dials, of course, agree, and indicate the same hour.

In our drawings we have indicated the way-time in divisions of five minutes; but when manufactured by regular dial-makers, with the nice mechanical means of exact subdivis-

ion which they possess, smaller fractions could be indicated. An additional gearing might be attached to our minute-hand for the way-time; but this would uselessly complicate an invention for which we claim extreme simplicity.

To use our improved watch requires no mental effort or careful scanning of figures and intricate names, as the name of only one place is visible at a time, and no change in the hands is effected. The way-dial which the traveler has to consult more frequently while away from home is in the usual relative position with the pendant of the watch.

We do not confine ourselves to any precise position of the dials, but have indicated such as seem to us the most easily understood and used. Many modifications might be suggested. Thus merely inscribing the names of cities on an ordinary watch-dial and enameling or engraving the hours on a movable watch-crystal would constitute for a traveler's watch a good equivalent of the more convenient, perfect, and artistic arrangement we have described.

The watch being constructed, substantially as described, its use is most simple. If the traveler does not desire to ascertain the time of any particular place of residence, and merely desires to know the way-time, he has only to bring the name of the city in which he has regulated his watch under the hole *f*, and then by bringing other names, either east or west of that locality, he has the way-time; but if he desire to have afterward both the home and way time, he fixes the twelve-o'clock figure of

the home-time dial opposite the name of the city he inhabits and opposite the hole *f*, so that the hours on both dials correspond. This adjustment can remain thus as long as he considers the same city his home. When traveling, he obtains the way-time by moving the milled head *C* so as to bring way localities opposite the hole *f*. In the drawings the home is supposed to be New York and the way-time that of Chicago. Both hands indicate on the home-dial fifteen minutes past one, and on the way-dial the hour-hand indicates twenty minutes past twelve o'clock, there being a difference of fifty-five minutes between the two cities.

What we claim as our invention, and desire to secure by Letters Patent, is—

1. In watches more particularly intended for travelers, the dial *F*, having a hole, *f*, through which can be read the name of one of the places of which it is desired to ascertain the time, and on which are inscribed ordinary figures indicating the hour and minutes.

2. The detachable segment *hh*, on which the names of cities and places are inscribed, the whole constructed and operated substantially as herein set forth.
